UNITED STATES PATENT OFFICE.

ARTHUR H. BALLARD, OF BOSTON, MASSACHUSETTS.

AEROPLANE RUNWAY.

Application filed November 14, 1923. Serial No. 674,650.

This invention relates to aeroplane runways and consists in improvements designed to facilitate either the alighting or taking-off of an aeroplane or both, more particularly under conditions where the space available for that purpose is restricted.

The invention will be best understood by reference to the following description when taken in connection with the accompanying 10 illustration of one specific embodiment thereof, while its scope will be more particularly pointed out in the appended claims.

In the drawings,—

Fig. 1 is a longitudinal, sectional elevation of a device embodying one form of the invention, a portion of the structure intermediate its ends being broken away to reduce the length of the figure;

Fig. 2 is a cross sectional elevation of the 20 device shown in Fig. 1; and

Fig. 3 is a longitudinal, sectional elevation on an enlarged scale showing the details of one of the units of which the movable runway carrier is composed.

Referring to the drawings and to the embodiment of the invention there submitted for illustrative purposes, the runway is carried by a suitable support 5, herein comprising a structural steel skeleton framework. 25 The latter may, if desired, be erected on a solid foundation, but for use on shipboard it may be provided with means to check more or less the effect of the vessel's lateral rolling, and the same or similar means may be utilized on land to check or cushion the effect of lateral shocks such as may be due to the aeroplane landing obliquely on the runway.

For this purpose in the illustrative embodiment the structure 5 is shown capable of a rocking movement about a longitudinal axis, being provided midway its width with a plurality of roller supports 7 resting on bearing rolls 8 arranged in suitable recesses 40 provided in the bedplate 9, which latter may be here regarded as a part of, or erected on the deck or structure of, a vessel, the direction of length of the latter coinciding with that of the runway, although a similar construction may be employed on land.

The structure 5 is maintained laterally in a normal position of equilibrium by cushioning supports arranged on its opposite sides. Herein these comprise one or more 45 upright cylinders 11 pivotally secured at the base 9 on each side of the structure and ca-

pable of slight sidewise rocking movement, there being provided within each cylinder a piston 13 secured to the rod 15 depending from the structure 5. Within each cylinder 60 beneath its piston is a compression spring 17, the arrangement being such that on the rolling of the vessel from one side to the other the spring on the elevated side of the vessel compresses more or less, checking or minimizing the departure of the runway from its normal level position and tending to maintain that position without substantial lateral inclination.

Mounted on the described structure there 70 is provided a runway presenting an upwardly exposed alighting and take-off surface, such runway being of suitable width to receive the running gear of an aeroplane and of a suitable length. No attempt is made in 75 the drawings to show a definite length since the principles of the invention may be carried out in a structure of very great length, but, as will be understood from the following description, the employment of this invention makes it possible to bring an alighting 80 aeroplane to rest in a space relatively small as compared with that ordinarily required, so that the length of the structure may be adapted to a comparatively limited 85 space.

In the described embodiment of the invention, this runway surface is movable in the direction of the length of the structure and is composed of units carried by an endless 90 carrier. This carrier is composed of endless sprocket chains 21 (Fig. 1), one on each side of the runway, extending substantially the entire length of the structure and passing over a sprocket wheel 23 at one end and a 95 second sprocket wheel 25 at the opposite end thereof. These chains are connected to form a unitary carrier by a series of transverse rods 27 arranged at intervals, each rod being provided at its opposite ends with a flanged wheel or roller 29 running in a groove shaped 100 guide presented by a channel member 31. The channel members are secured to the structure 5 and form on each opposite side (see Fig. 1) a closed endless path for the 105 wheels or rollers 29, so that when the carrier is propelled through one of the sprocket wheels it is guided both vertically and laterally in a fixed path.

Opposite sprocket wheels 23—23 and 110 25—25 are mounted upon shafts 33 and 35 respectively which turn in bearings 37 se-

cured to the frame of the structure 5, and one of said shafts, herein the shaft 33, is connected to driving means, as an electric motor 39 (shown only in Fig. 2). The latter drives 5 the sprocket wheels and carrier through the driving belt 41 and is preferably provided with controlling devices, herein represented conventionally by the switch 43 and rheostat 44, whereby it may be driven in either 10 direction and at controlled rates of speed.

The runway surface is herein composed of a series of plates 45 extending across the entire widths of the runway, there being one such plate for each of the rods 27. As best 15 shown in Fig. 3, each plate is movably connected, herein by a hinged connection 47 along its rear transverse edge, to a bracket 49 U-shaped in end view (Fig. 2), the plate being adapted to rest through its opposite 20 transverse edge on the rear end of the next preceding bracket 49, so that when the plates are in their depressed position (shown in full lines in Fig. 3) they present at the upper side of the carrier a substantially flat 25 horizontal runway. The brackets 49 are supported by the transverse rods 27, there being a supporting bracket at each opposite end of each rod and other intermediate brackets as may be required, there being 30 herein shown (Fig. 2) two such intermediate brackets for each unit. Between the forked ends of each bracket the rod 27 carries a supporting roller 51 adapted to track with a stationary supporting member, such as the 35 rail 53. These rails are shown (Fig. 1) as extending the entire length of the structure, both top and bottom, so that they not only assist in sustaining the weight of the aeroplane when on the runway, but maintain at 40 all times the proper relation between the supporting plates 45 and their associated parts, as will be more fully described.

Referring more particularly to Fig. 3, the plate of each unit is adapted to be raised 45 to an inclined position, such as is there indicated in dotted lines (or in full lines at the top of Fig. 1), through the action of the compression spring 55. The lower end of 50 this spring is connected to and housed within the cylindrical casing 57, while the upper 55 end is attached to the plate 59 pivotally secured to the under side of the plate 45. The bottom of the casing 57 is pivoted at 61 to an arm 63, the bifurcated end of which is supported on the shaft 27. The opposite 65 end of the arm rests upon the track 53 through the roller 65.

To hold the plate 45 flat when depressed under a force sufficient to compress the 60 spring 55 within its casing there is provided a releasable latching means. In the embodiment of the invention herein shown this comprises a cylinder member 66 pivotally secured to the arm 63 and containing the 65 sliding plunger 67, the latter having a joint-

ed connection to the bottom of the plate 45. If the plate is depressed against the spring, the plunger descends until a notch in the side thereof is engaged by the spring-pressed detent 68 carried by the cylinder 66, and the plate is thereby locked in its depressed position. The detent projects from the side of the cylinder and is provided with an enlarged head 69 adapted to be engaged by the end of a trigger lever 70 pivoted at 71 75 on the casing 66 and having a depending end adapted to be engaged by suitable releasing mechanism.

To automatically release the latch when and as required there is provided a dog 72 80 pivotally mounted in the bracket 73 secured to one side of the rail 53 and yieldingly pressed upward by the spring 75 within the path of the lower end of the trigger lever 67. When the carrier is moved counterclockwise 85 or left-handedly, as viewed in Figs. 1 and 3, the dog is effective to throw the trigger and release the spring. When the carrier is moved in the opposite direction and the lower end of the latch lever 70 contacts with 90 the dog, the latter yields without releasing the latch.

Each support may have a plurality of springs 55, there being preferably a spring 95 for each bracket 49. The springs (by means not herein shown) may be susceptible of ready connection to and disconnection from their respective plates, or may be individually adjustable, so that adjustment may be made from time to time in the resistance offered by the different plates to meet the different conditions presented by aeroplanes of 100 different types or sizes. Where a spring is provided the corresponding latching parts described are also provided. One or more 105 releasing dogs are provided to cooperate with each trigger lever. A number of these may be distributed along each rail 53, but when the runway is operated as herein described one dog for each rail is sufficient, the same 110 being located near the far end of the runway or the right-hand end as viewed in Fig. 1. In Fig. 1 the springs and other connecting parts are omitted from all but two of the 115 plates.

When the runway is in condition for receiving an alighting plane the surface plates 45 in that portion of the runway lying within the path of the plane, or on the upper side of the carrier, are held at the inclination represented by full lines in Fig. 1 through the compression springs 55, thereby presenting to the path of the plane a series of movable inclined members adapted to yield when engaged by the wheels or other 120 running gear of the aeroplane and absorb a part of the energy of motion and thereby check the momentum of the plane.

The near end of the runway, or that 125 which the descending plane first approaches, 130

is provided with a guide plate 77 which protects the end of the runway and has an inclined lip 79 extending down into close approximation to the level of the hinged seats of the surface plates. This plate, which may be extended away from the runway to any desired length, not only provides a guideway for the runway, but also insures the surface plates being pressed into their lowermost latched positions as they pass under the guide plate in either direction of the carrier travel.

At the opposite end of the runway as the supporting plates 45 are carried over the sprocket wheel 25, their free edges pass into engagement with a series of rolls 81 carried by a stationary support 83 having flared walls, so that as the carrier travels around the sprocket in a clockwise direction the edges of the supporting plates engaging the rolls are gradually moved inwardly, compressing the springs until they reach the latched position, in which position they are held as they travel along the lower horizontal path of the carrier. In traveling along the lower horizontal path the plates pass over a series of supporting rollers 85. At the opposite end of the runway there is provided a second series of rolls 87 carried by the stationary support 89, these rolls, however, being arranged concentrically with the sprocket wheel 23.

The construction is such that when the motor 39 is actuated to drive the carrier in a counterclockwise direction (as viewed in Fig. 1), each supporting plate is thrown up into its inclined position as soon as its triggers engage the dogs 72, so that, in whatever position the plates may previously have been, by moving the carrier counterclockwise the entire series of plates presented by the top of the runway may be released and conditioned to receive a descending plane. With equal facility, however, the runway may be converted to present a substantially flat surface by starting the motor in the opposite direction and reversing the movement of the carrier. As the inclined plates engage the flared series of rollers 81 their springs are gradually compressed and are latched in flat position as they emerge from the rollers and pass over the supporting rollers 85. The continuance of this flat latched relation is insured by the guide plate 79 before they emerge from beneath the same. The rollers 87 support the edge of the plates as they ascend over the sprocket 23 presenting them in proper relation to the guide plate 79.

When a plane alights on the runway and travels along the same, with the supporting plates conditioned as shown in Fig. 1, it encounters a yielding resistance at each plate which is overcome by the momentum of the plane, successive plates moving down

and being retained in their depressed position by their respective latch levers. The depression of the plates, however, is only accomplished by the depression of the springs 55 which checks the momentum of the plane and gradually brings it to rest with a length of run which is relatively short. The checking effect may be increased to any required degree and the effective length of run increased for a given length of runway, by simultaneously driving the carrier in the direction opposite to the travel of the plane, thereby increasing to any required extent the rate at which the inclined plates are presented to the advancing plane.

By thus presenting a series of yieldable obstructions within the advancing path of the plane, and additionally by positively moving such obstructions in a direction opposite to the travel of the plane, the latter may be brought to rest within a comparatively restricted space and by suitably proportioning the springs this may be accomplished by a gradual resistance as contrasted with a succession of shocks.

On the other hand, when it is desired to utilize the runway for the taking-off of a plane, it may be quickly converted into a substantially level runway by first reversing the movement of the carrier and then stopping the same. If desired the runway may be set in motion during the taking-off of an aeroplane.

Preferably the structure 5 is extended above each side of the runway to provide lateral guideways 91 and prevent the plane from leaving the runway laterally, such guides being herein shown as provided with vertically arranged rollers 93.

While I have herein shown and described for the purposes of illustration one illustrative embodiment of the invention, it is to be understood that the latter is not limited to the mechanical details or relative arrangement of parts herein shown, but that extensive deviations may be made without departing from the spirit of the invention.

I claim—

1. An aeroplane runway comprising an endless traveling carrier having means to present an exposed aeroplane supporting surface, the latter comprising a series of supporting plates with connected springs, the latter being adapted to hold said plates at an inclination and presenting a series of yieldable inclined obstructions adapted to yield under the advance of the aeroplane, means to hold the supporting members against the action of the springs to present a substantially flat runway, devices to release the supporting members as required, the same comprising releasing devices acting on said holding means when the carrier is moved in a given direction to place the run-

- way in a condition to receive an alighting aeroplane, means to place the runway in a substantially flat condition for the take-off of an aeroplane when the carrier is propelled 5 in the opposite direction, a system of guiding supports for said carrier, and means for driving the carrier including starting and stopping and speed varying devices.
2. An aeroplane landing presenting in the 10 path of the aeroplane a series of inclined members, springs normally holding said members in opposing relation to the advance of the aeroplane, and devices to hold said members in unopposing relation when the 15 opposition of the springs is overcome by the aeroplane.
3. An aeroplane runway presenting in the 20 path of the aeroplane a plurality of devices held in opposing relation but movable out of opposing relation when engaged by the aeroplane, the same having means to absorb energy from the aeroplane through the movement of said devices thereby to check its momentum, and means to hold the devices in un- 25 opposing relation when so moved.
4. An aeroplane landing comprising a runway presenting for engagement in succession by said aeroplane a series of hinged opposing energy absorbing obstructions to check momentum and convertible at will to present an 30 unobstructed portion for starting.
5. An aeroplane runway comprising a 35 movable carrier composed of units, each unit having a plate adapted to be held at an inclination to the travel of the aeroplane, springs resisting depression of said plates, a latch to hold said plates when depressed, devices to trip the latch, and a stationary guide plate for the end of the runway.
- 40 6. An aeroplane runway comprising a sup- port with a runway surface, a connection to said support permitting lateral tilting of said runway relative to said support, and devices to check the tilting movement.
7. An aeroplane runway comprising an 45 endless traveling carrier having means to present an exposed aeroplane supporting surface, with a series of yieldable obstructions adapted to yield under the advance of the aeroplane, means to retain said obstructions so as to present a substantially flat runway, devices to release the obstructions to present an obstructed runway, and means to move the carrier in the direction opposite to the direction of travel of the aeroplane.
8. An aeroplane runway comprising a 50 traveling carrier presenting inclinations to the path of the aeroplane, means for causing the travel of the runway, and means operated by the movement of the runway for converting the same to present a substantially flat portion for starting.
9. An aeroplane runway having a series 55 of momentum checking obstructions in the path of the aeroplane, and means operable by the movement of the runway for converting the latter to present a substantially unobstructed portion for starting.
10. An aeroplane runway having a move- 60 able surface embodying a plurality of move- able members, with means for holding them to present a substantially flat portion for starting, and means to release said members by movement of the surface to present a suc- 65 cession of momentum checking obstructions to the path of the aeroplane.
- In testimony whereof, I have signed my name to this specification.

ARTHUR H. BALLARD.
